UNITED STATES PATENT OFFICE.

FRIDOLF F. BACKSTROM, OF CHICAGO, ILLINOIS.

DRUM-FORMING MACHINE.

Application filed September 15, 1923. Serial No. 662,994.

To all whom it may concern:

Be it known that I, FRIDOLF F. BACKSTROM, a citizen of the United States, residing at Chicago, in the county of Cook and 5 State of Illinois, have invented certain new and useful Improvements in Drum-Forming Machines, of which the following is a specification.

This invention relates to means for expeditiously making the cylindrical portion of a builder's sieve, known in the trade by the name of "riddle" for sifting sand and the like, and the invention consists in the novel combination and arrangement of parts hereinafter described in detail, illustrated in the accompanying drawing and more particularly pointed out in the appended claims.

In the drawing—

Figure 1 is an edge view of a machine 20 embodying my invention.

Figure 2 is a face view of same with the supporting stand omitted and the operating rod broken off.

Figure 3 is a vertical section taken substantially on the line 3—3 of Figure 2.

In the several views 2 represents a vertical plate or casting with a foot portion 2' and back-bracing or strengthening ribs 3 and 4. Said plate is cast with an anvil portion 5 which engages the inner periphery of an upper portion of the cylindrical portion of the riddle, while a similar lower anvil portion 6 serves as a supporting shelf upon which the lower portion of said riddle rests, 30 the dotted lines in Figure 1 indicating the changed position of the riddle when it is nailed from the inside against the lower anvil portion 6. The upper anvil portion 5 and its plate 2 are cast with supporting ribs 7 and 8 which project at right angles from said plate and anvil portion. Lower down another projection on plate 2 is in the form of a bearing lug 9 through which extends a vertical bore 10 which is slidably 40 engaged by a pull-rod 11 which may be conveniently actuated by means of a treadle 12 that is fulcrumed at 13 to a leg or other fixed part of the bench, table or stand on which the machine is mounted, and pivoted to the 45 rod at 14. The rod 11 is bent rearwardly at 15, the rearward bent or inclined portion thereof passing through an opening 11' in the plate 2 and then rebent into parallelism with its upper portion as at 16 and extending 55 down to the treadle 12 through a bench

or support 17 herein shown with legs 18 and 19.

The anvil portions 5 and 6 are diametrically opposing segments conforming approximately to the curvature of the riddle sides or annulus 20, the ends of which are beveled portions 21 and 22 which overlap each other over the upper anvil 5 where they are adapted to be nailed or otherwise secured together to form a substantially unbroken annulus. The latter is held clamped in its ring-form during such fastening of the overlapping beveled ends by means of oppositely movable clamp members 24 and 25 engaging the outer sides of the cylinder 60 form and similar inner clamp members 26 and 27 which engage the inner periphery of said form. The members of each pair of clamp members are moved by means of toggle links actuated through said rod 11. Said links are placed opposite an opening 28 in the plate 2 to permit projection of the links to both the inner and outer clamp members. To the pair of outer and inner 70 clamp members 24 and 26 are, respectively, pivoted links 29 and 30, the former's pivot being in an enlargement 31 on the upper portion of the clamp member 24. The inner end of the link 29 is pivoted at 32 to one end of a link 33 the middle portion of which is expanded and bored to receive the rod 11 as shown best in Figure 3. To the opposite end of said link 33 is pivoted the inner end of a link 35 the outer end of which is pivoted at 36 to the clamp member 25. The inner pivots for the toggle links extend to both front and rear of the opening 28, the toggle links for the outer clamp-members passing back of the plate 2 while the toggle links for the inner members pass in front of said plate 2, as indicated in all the views. The links for forcing the inner clamp members 26 and 27 toward or away from the outer clamp members include said link 30 and a similar link 37, which are respectively pivoted at 38 and 39 to the inner clamp members and pivoted at 40 and 41 to a connecting link 42, similar to the link 33 in form and engagement with the rod 11. The links 33 and 42 are adjustably secured to said rod 11 for adjustment toward and from each other, or for varying the normal space between the co-operating pair of clamps 24 and 26 and 80 25 and 27, by means of nuts 43 and 44 which have threaded engagements with said rod 110 105 110

11 and operate against opposite sides or edges of the link 42. Similar nuts 45 and 46 are adapted to adjust the link 33 along the rod 11 in the same manner.

5 The lower ends of the four clamp members are pivoted to the back-plate 2, or to boss or lug extensions thereon. The said pivot for the clamp-member 24 is indicated at 47 and that for the member 25, at 48.

10 The back-plate pivots for the inner clamp-members 26 and 27 are shown at 49 and 50. Between the latter are back plate projections 51 and 52 following the curvature of the anvil portion 6 and together with it forming trough-like recesses to engage the lower portion of the drum or cylinder 20 or to assist in positioning said work 20 and, in connection with the clamp-members, to hold the work, or 20, while being nailed or

15 secured as at 23 where the nails 23 are shown driven from the outside against the anvil portion 5. The clamps are then released and the joint 21—22 placed over the anvil portion 6 to be additionally secured

20 by driving nails from the inside against the anvil 6, as suggested by dotted lines to the right in Figure 1.

Having thus described my invention, I claim as new and desire to secure by Letters

30 Patent—

1. A drum-forming machine of substantially annular form, which form consists of a series of clamp-members movable toward and from each other, and a pair of diametrically arranged immovable anvils on inner and outer faces respectively, and means for moving said clamps simultaneously.

2. A drum-forming machine, clamp-members movable inwardly and outwardly

40 which provide a substantially annular space adapted to receive an annulus or cylinder and inwardly and outwardly movable clamp-members between them, a pair of oppositely disposed and stationary anvils,

45 and means for contracting said space.

3. A drum-forming machine consisting of a series of movable clamp-members, one pair thereof adapted to engage the inner periphery of a drum or cylinder expansively, while another pair thereof is adapted to engage the outer periphery of said drum or cylinder contractively, a lever-mechanism connecting said clamp-members to move co-operatively, and a pair of anvils engaging, respectively, the outer and the inner peripheries of said drum or cylinder, said anvils being arranged in a plane passing substantially between said clamp-members.

4. In a drum-forming machine, the combination of an upper with a lower support for, respectively, an inner and an outer portion of the peripheries of a drum or hollow cylinder, of curved and movable clamps adapted to engage therebetween opposite sides of said drum or hollow cylinder, and means for operating said clamps simultaneously.

5. The combination with oppositely moving and co-operating clamps arranged to form a substantially annular recess to enclose an open ring or annulus, of means for moving said clamps to contract said recesses and clamp said work between said clamps, and anvils on which the ends of said ring or annulus are nailed together.

6. The combination with a back plate, of oppositely disposed pairs of clamps movable toward and from each other and forming therebetween a substantially annular recess adapted to receive work in the form of a drum or hollow cylinder, of diametrically disposed nailing anvils adapted to support inner and outer portions of said work, and means for moving said clamps to grip said work.

In testimony whereof I have hereunto signed my name.

FRIDOLF F. BACKSTROM.
